UNITED STATES PATENT OFFICE.

JOHN L. GUERRANT, OF SEDALIA, MISSOURI.

GRAIN-CAR DOOR.

1,410,565.

Specification of Letters Patent. Patented Mar. 28, 1923.

Application filed May 13, 1919. Serial No. 296,854.

To all whom it may concern:

Be it known that I, JOHN L. GUERRANT, a citizen of the United States, and resident of Sedalia, in the county of Pettis and State 5 of Missouri, have invented certain new and useful Improvements in Grain-Car Doors, of which the following is a specification.

This invention relates to freight car doors, and more especially to grain doors, it being 10 the object of the invention to provide in combination with an ordinary outer sliding door, an inner door mounted for sliding movement along the inner side of the car wall to and from the door opening and provided with means for the convenient filling 15 of the car with grain and for relieving the pressure in opening the car, for starting the flow or discharge of grain, or for taking out the merchandise or freight which jams or 20 wedges against the inner door, so that the pressure can be relieved and the door slid open.

A further object is the provision of such a grain door of novel and improved construction, in connection with novel means for 25 holding the door closed, rendering the same grain tight, and resisting the outward pressure against the relief door, the construction also being such that leakage and theft (without 30 breaking the seal of the doors) are eliminated.

Another object is the provision of hinged bars to swing between the door posts or 35 jambs and the inner grain door and arranged to overlap the relief door and hold it closed against outward pressure, as well as retaining the grain door in place and providing a tight joint between said door and the door frame.

40 A still further object is the provision of novel means for holding said bars either against the door or out of the way against the door posts.

With the foregoing and other objects in 45 view, which will be apparent as the description proceeds, the invention resides in the construction and arrangement of parts hereinafter described and claimed, it being understood that changes can be made within 50 the scope of what is claimed without departing from the spirit of the invention.

The invention is illustrated in the accompanying drawings, wherein—

55 Figure 1 is an outside view showing the inner grain door in closed position, and the outer door slid open.

Figure 2 is an enlarged vertical section on the line 2—2 of Figure 1.

Figure 3 is an enlarged vertical section taken approximately on the line 3—3 of 60 Figure 1, without cutting the relief door.

Figure 4 is a horizontal section taken on the line 4—4 of Figure 1.

Figure 5 is an enlarged end view of the 65 lock for the doors.

Figure 6 is an enlarged detail view of one of the hinged bars showing the bolt receiving ring.

Figure 7 is a horizontal section through a 70 locking bar showing a modification.

Figure 8 is a similar view showing the bar 75 swung against the frame.

The present improvements are incorporated in the ordinary car construction, without requiring prohibitive alterations. The 80 door frame forming a part of the side wall of the car includes the vertical door posts or jambs 7 as usual at the opposite sides of the door opening, and an ordinary outer door 8 is suspended for longitudinal movement 85 along the outer side of the car wall to and from the door opening, as usual. It is preferable to use the track and hanger as disclosed in my copending application filed November 19, 1917, Serial No. 202,831, which 90 is wind and weather proof. The hanger 9 comprises a plate secured to and projecting upwardly from the upper edge of the door 8 and having a T-head, the flanges of which 95 rest upon rollers 10 mounted within the channels 11 of the track which extends along the car wall above the door opening from the vertical door stop 12 to a suitable distance toward the opposite side of the door opening, permitting the door to slide freely 100 to closed and open positions. The lower edge of the door 8 is retained against the sill by means of guides 13.

Coming to the inner grain door 14, which 105 may be of wood or other suitable construction, this door is also mounted for longitudinal sliding movement, and is located at the inner side of the car wall, being also preferably suspended by a track and hanger as used for the outer door. Thus, the hanger 105 15 comprising a plate secured to the upper edge of the door 14 has the T-head moving freely on the rollers 16 mounted in the channels 17 of the track extending along the inner side of the car wall over the opening 110 and to one side thereof where a housing 18 is preferably provided to receive the door 14

when it is slid open, although this housing 18 need not be used in all cases. The chief object in using the housing 18 is to prevent merchandise from preventing the opening 5 of the door 14, although this is not strictly necessary, because access can be had into the car through the relief door to remove the merchandise. A vertical stop 18' is secured to the inner side of the car wall at that side 10 of the opening opposite to the housing 18 to limit the movement of the door 14 when slid to closed position.

The door 14 has the vertical stiles 19 at its side edges forming the shoulders 20 extending vertically and facing one another at the outer side of the door 14 to move substantially flush with the door posts or jambs 7, as seen in Figure 4. These stiles 19 are adapted to bear against the inner sides of 20 the jambs 7 to take up the outward pressure against the door.

The door 14 is provided near its upper end with a filling opening 21 normally closed by the door 22, hinged, as at 23, to 25 swing open outwardly, and any suitable lock 24 can be used for holding the door 22 closed. This door when swung open permits the grain to be delivered into the car behind the door 14 by the usual chute or the like.

30 The door 14 is further provided with a relief opening 25 extending from a point between its upper and lower ends to the lower end thereof and being of a width to extend close to the shoulders 20. This opening 25 is closed by a relief door embodying upper and lower sections 26 and 27, the upper section of which is hinged, as at 28, to the door 14 at the upper edge of the opening 25 to enable the relief door to swing 40 open outwardly and upwardly for relieving the pressure and starting the flow of grain, or permitting the merchandise or freight to be taken out from behind the door. The sections 26 and 27 are hinged together, as at 45 29, permitting the joint to break outwardly.

A sill plate 30 is provided on the sill of the car at the lower end of the door opening, and is preferably flush with the floor of the car. This sill plate 30 has a longitudinal 50 slot or groove 31 over which the door 14 is movable, and the lower edge of the relief door section 27 has a depending flange or lip 32 movable in the slot or groove 31. The outer wall of the groove 31 is vertical or 55 square for the flange 32 to bear outwardly against, thereby receiving the outward pressure against the lower edge of the relief door, and preventing said lower edge from being forced open outwardly by the pressure 60 of the grain or freight. The inner wall of the groove 31, however, is inclined, whereby should any grain, ore or other matter accumulate and even harden within said groove, the door 14 in being closed will cause 65 the flanges at the lower end thereof to force

the accumulation out of the groove. In this way, the groove 31 will be cleared of matter accumulated therein, thereby avoiding the objection of the possible difficulty in sliding the door 14 closed should ore, cement or other matter collect and harden within the groove. Naturally, the lower flanges of the door in striking the matter within the groove will, by the endwise pressure, break it and force same upwardly and inwardly out of the groove. Plates 33 are secured to the lower end of the door 14 at the stiles, and have depending flanges 34 to also move in the groove 31.

Locking bars 35 are provided at the opposite sides of the door opening for holding the inner door 14 and its relief door closed. Each of these bars comprises the plates 36 and 37 with a filler plate 38 between them, and the plate 36 forms the leaf of a hinge, being provided with the hinge butts 39 slidably and rotatably embracing a vertical hinge rod 40 extending through the hinge butts 41 of a hinge leaf 42 secured to the inner side of the respective post or jamb 7. 90 The hinge butts 41 are spaced apart sufficiently to permit of vertical movement of the hinge butts 39 and the bar 35, this bar extending along the post or jamb at the inner corner thereof and therefore being 95 slidable longitudinally of itself or vertically of the car wall. These bars are swingable between the door 14 and jambs 7 in the corner between them, and said bars are hinged to the jambs directly adjacent to the 100 inner sides thereof so as to swing flatly against the door 14, from one edge of each bar to the other edge, and with the hinged edges of the bars presented to and abutting the shoulders 20, as seen in Figure 4. This 105 will firmly hold the door 14 in place, and the sill plate 30 has, as a part of the door frame, a slot or recess 43 at each end of said plate below the respective bar 37 and extending from the corresponding jamb 7 toward the opposite side of the door frame to receive the lower end of the bar 35 from edge to edge. Thus, when the bars 35 are 110 swung against the door 14, the vertical movement thereof, permits them to drop or slide downwardly with their lower ends fitting snugly in the slots or recesses 43, thereby holding said bars against the door. The bars 35 when swung against the door 14 overlap the ends of the relief door, thereby preventing outward movement thereof, and the lower ends of the bars 35 in fitting 115 in the slots or recesses 43 will resist the outward pressure against the relief door where the greatest security is necessary owing to 120 the pressure from within the car. The bars when swung against the door 14 rest flatly against the door practically flush with the stiles 19, and when the bars 35 are swung 125 away from the door 14 they swing flatly 130.

against the jambs 7, permitting the relief door to swing open outwardly, as when starting the discharge of grain or the removal of freight or merchandise in emptying the car. Furthermore, when the bars 35 are swung against the jambs, the door 14 can also be slid open. By the provision of the movement of the lower ends of the bars 35 into the slots or recesses 43, the lower ends of said bars are firmly braced and held against outward sagging or springing movement under the pressure against the relief door, and the flange 32 will prevent the lower edge of said relief door from springing or sagging outwardly between the bars 35.

Means are provided for securing the bars 35 to the door 14 above the relief door, to assist in holding the parts in place. Thus, nuts 44 are embedded in the door 14, and suitable bolts 45 are insertable inwardly through the bars 35 to engage the nuts 44 and clamp said door and bars together, as seen in Figure 4. The bars are preferably provided with means for the insertion of the bolts permitting them to be readily aligned with the nuts 44. Thus, the plates 36 and 37 of each bar 35 have openings 46, and the plate 38 has a larger opening 47 in which a ring 48 is movable, the opening 47 thereof being exposed through the openings 46. Thus, the bolt 45 can be readily inserted into the ring 48 which can be moved vertically and horizontally within the opening 47 so that the bolt can be readily brought into engagement with the nut. Thus, even though the bar 35 is movable vertically, and there is possibility of relative horizontal displacement between the bar 35 and door 14, the bolt can be shifted to conveniently introduce the same into the nut 44.

In order to hold the bars 35 out of the way against the jambs 7 when they are not in use, the sill plate 30, forming a part of the door frame, has transverse slots or recesses 49 extending along the jambs and into which the lower ends of the bars 35 can drop when they are swung flatly against the jambs, thereby preventing said bars from being swung away from the jambs and damaged during the loading or unloading of the car. Furthermore, nuts 50 can be embedded in the jambs 7, so that the bolts 45 can be inserted in the opposite direction through the bars 35 and screwed into the nuts 50 for clamping the bars against the jambs. It will also provide means for holding the bolts 45 when they are disconnected from the door 14. It is preferable to use a standard bolt, so that the loss thereof enables another ordinary bolt to be used.

It is also desirable to use a lock 51 for controlling the movement of the outer and inner doors. This lock embodies a casing or supporting member 52 secured in any suitable manner to the post or jamb 7 across

which the doors are movable, and at that side of the jamb opposite to the door opening. This member 52 has a slot or opening 53 extending therethrough transversely of the car wall, and latch rings 54 and 55 are disposed in the opening 53 for transverse movement through the car wall, the joint diameters of the two rings being slightly greater than the thickness of the car wall or the space between the doors 8 and 14. These rings are retained in the member 52 by means of bolts 56 extending therethrough, yet permitting of the inward and outward movement of said rings. In using this lock, the outer door 8 is provided at its inner side and near that edge adjacent to the door opening when the door 8 is opened, with a recess or slot 57 to receive the ring 55, as seen in Figure 4. Therefore, after the door 8 is slid open, the ring 55 will be able to enter the recess 57, so that when the door 14 is slid open it will push the ring 54 outwardly, and the ring 54 in contacting with the ring 55 will thrust the latter outwardly into the recess 57. The door 14 when open will prevent the rings from moving inwardly, so that the outer door 8 cannot be slid closed until the inner door is first closed, thus releasing the inner ring 54. The outer door can then be slid closed, and the rings will be forced inwardly and held in this position, with the ring 54 projecting inwardly into the path of the door 14. Therefore, when the outer door is in closed position, the inner door cannot be opened by a person within the car, for purpose of theft, because the inner ring 54 will prevent the inner door from being slid open as long as the outer door is closed. However, when the seal of the outer door is broken and said door slid open, this will, by bringing the recess 57 opposite to the ring 55, permit the rings to move outwardly for opening the inner door.

Figures 7 and 8 illustrate a modification, wherein the locking bar 35 is hinged to the door 14, instead to the door frame as in Figure 4. Thus, the hinge plates or leaves 42 are secured to the stiles 19 of the door 14, instead of being secured to the door posts or jambs 7. Otherwise, the construction is the same as that above described, it being noted, however, that the locking bars 35 are carried by the door 14, so that these bars will move with the door when it is slid open and closed. The bars 35 are movable into the recesses 43 and 49 in the sill plate 30, and said bars are also fastened to the door 14 or jambs 7 by means of the bolts 45, which can also be used for holding the bars to the door 14 when it is slid.

Having thus described the invention, what is claimed as new is:—

1. The combination of a door frame having a sill, a door slideable across the inner

side of the door frame, and having a relief door swingable outwardly within the door frame above the sill, and a locking bar mounted for swinging and longitudinal sliding movement, to swing against the doors, the sill having a recess over which the relief door is swingable when opened, and arranged to receive the lower end of said bar when swung against the doors, to resist the outward pressure of the relief door.

2. The combination of a door frame, a door movable to a position across the inner side thereof, a series of hinge butts carried by one of said parts, a locking bar having a longitudinal series of hinge butts at one edge movable longitudinally between and slidably and hingedly connected to the aforesaid hinge butts, so that said bar is braced at points along the length against outward pressure, and a relief door carried by the aforesaid door to swing outward within the door frame, said bar being swingable against the doors, and the door frame having a recess at one end of the bar to receive said end of the bar and resist outward movement of the relief door.

3. The combination of a door frame having a sill and a jamb, a door slidable across the inner side of the door frame and having a lower relief opening and a shoulder to move adjacent to said jamb, a relief door to close said opening and movable outwardly within the door frame when opened, and a locking bar extending along the jamb and connected to the door frame for longitudinal sliding movement and to swing against said doors with one edge presented to said shoulder, the sill having a recess to receive the lower end of the bar when it is swung against the doors and thereby resist the outward pressure of the relief door.

4. The combination of a door frame having a jamb, a door movable to a position across one side of the door frame, a locking bar connected to one of said parts for longitudinal sliding movement and to alternately swing against the door and jamb, the door frame having a slot at one end of said bar extending from the jamb toward the opposite side of the door frame, to receive said end of the bar from edge to edge and brace it in position against the door, and an outwardly-opening relief door carried by the aforesaid door to be held closed by said bar.

5. The combination of a door frame having a jamb, a door slidable across the inner side of the door frame and having a shoulder to move adjacent to the jamb, a locking bar hingedly connected at one edge to the frame along the jamb directly adjacent to said inner side of the door frame, so as to swing away from the jamb flatly against the door from one edge of the bar to the other with the hinged edge of the bar presented to said shoulder, means for holding

the bar against the door, and an outwardly-opening relief door carried by the aforesaid door to be held closed by said bar.

6. The combination of a door frame having a jamb, a door slidable across the inner side of the door frame and having a shoulder to move adjacent to the jamb, a locking bar having one edge connected to the door frame, along the jamb directly adjacent to said inner side of the door frame for longitudinal sliding movement and for swinging movement between the jamb and door, so as to swing away from the jamb flatly against the door from one edge of the bar to the other with its hinged edge presented to said shoulder, the door frame having a slot at one end of said bar extending from said jamb toward the opposite side of the door frame to receive said end of the bar from edge to edge, and an outwardly opening relief valve door carried by the aforesaid door to be held closed by said bar.

7. The combination of a door frame having a sill, a door slidable across the inner side of the door frame and having a lower relief opening, said sill having a guide for the lower end of the door over which it is slidable, a relief door hinged to the first named door at the upper edge of said opening to swing outwardly and upwardly within the door frame, the lower edge of the relief door having means to fit down in said guide and bear outwardly against it when the relief door is closed, said relief door comprising hinged sections adapted to break outwardly and move within the door frame for withdrawing the lower edge of the relief door upwardly from said guide, and a longitudinally hinged locking bar to bear against the doors for preventing the relief door from breaking outwardly.

8. The combination of a door frame, a door movable to a position across one side of the door frame, a bar hingedly connected to one of said parts to swing between and against them, nuts carried by said door and frame, said bar having means to register with said nuts for the insertion of a bolt in opposite directions through the bar to engage the nuts for clamping the bar against either the door or frame.

9. The combination of a door frame, a door movable to a position across one side of the door frame, a bar hingedly and slidably connected to said door frame to swing between and bear flatly against said door and frame, said frame having recesses to slidably receive one end of said bar, one recess extending from said hinge toward the opposite portion of the frame to receive the bar and hold it against the door, and the other recess extending along the portion of the frame against which said bar bears to hold the bar thereagainst.

10. The combination of a door frame hav-

ing a sill plate, a door slidable to a position across the inner side of the door frame and having a lower relief opening, a relief door having an upper section hinged to the 5 first named door at the upper edge of said opening to swing outwardly within the door frame, and the lower section hinged to swing inwardly, the lower end of the first named door having a depending flange and the 10 lower section of the relief door having a depending flange, the sill plate having a longitudinal groove receiving said flanges, the outer wall of said groove being vertical for the sliding contact of the first named flange and for the pressure of the second named 15 flange, and the inner wall of the groove being inclined so that matter lodged therein will be dislodged by the first named flange, and to also facilitate the removal of the second flange from the groove when the relief 20 door breaks outwardly.

In testimony whereof, I hereunto set my hand.

JOHN L. GUERRANT.
